UNITED STATES PATENT OFFICE.

JEFFERSON R. LOWRY, OF MEMPHIS, TENNESSEE.

LIFTING-JACK.

1,250,910.

Specification of Letters Patent. Patented Dec. 18, 1917.

Application filed March 7, 1917. Serial No. 153,111.

To all whom it may concern:

Be it known that I, JEFFERSON R. LOWRY, a citizen of the United States, residing at Memphis, in the county of Shelby and State 5 of Tennessee, have invented new and useful Improvements in Lifting-Jacks, of which the following is a specification.

My invention relates to lifting jacks and has for its object; first, to provide a lifting 10 jack of light and convenient size which may be attached to a longitudinal support of regular cross section disposed parallel to the direction of stress, second, to provide a lifting jack which is readily and quickly ad- 15 justable along a support of regular cross section running parallel to the direction of stress, and thirdly, to provide a lifting jack readily adjustable along a longitudinal sup- 20 port of regular cross section running parallel to the lifting strain adapted to automatically clamp at any point on said support.

I attain these objects by the mechanism illustrated in the accompanying drawings forming a part of this specification in 25 which:—

Figure 1 is a front view of the lifting jack in working relation to a load.

Fig. 2 is a top plan view in partial section of the device.

Fig. 3 is an enlarged partial side view of 30 a portion of the mechanism.

Like characters of reference indicate like parts in the various views.

In the drawings 1 designates supports 35 which are of regular cross section and are disposed substantially parallel to each other and to the line of strain. These supports are held in position in any approved way and inasmuch as the means for positioning 40 them does not enter into my invention a description of the same is unnecessary to an understanding of my invention. A base plate A is formed of the two castings 2 clamped together by the bolts 3. On each 45 casting of said base plate A is disposed a downwardly extending ear 4. A pivot pin 5 is disposed upon said pair of ears 4 adjacent either end thereof and at a substantially right angle to the supports 1. Tilting levers 50 6 have outwardly extending arms 7, at the ends of which are formed vertical holes or inclosures 8. Said holes or inclosures 8 engage supports 1 and are fitted loosely there- to for purposes hereinafter described. Tilt-

ing levers 6 have inwardly extending arms 9 55 so disposed that they extend toward each other under the base plate A and almost meet. A compression spring 10 is disposed between the under surface of the base plate A and the ends of said arms 9 whereby the 60 levers 6 tend to assume a downwardly tilted position. Projections 11 upon arms 9 and a projection 12 upon the under surface of base plate A serve to retain spring 10 in a proper working position. 65

At the center of base plate A is a spherical recess 13 having an opening at the top and formed at the jointure of castings 2 by coincident hemispherical depressions in said castings 2. A jack screw 14 engages said 70 recess 13 with its lower end which is spherical in form. Said jack screw extends upwardly having threads 15 formed upon its cylindrical surface and terminates in a head 16 which is adapted to engage a wrench of 75 usual construction. A screw plate 17 engages the threads 15 of screw 14. A beam 18 is affixed to the upper surface of plate 17, said beam having an aperture through which jack screw 14 extends. The load 20 is engaged by the ends of beam 18 in such a manner that the head 16 of jack screw 14 may be properly manipulated. 80

The spring 10 pushes the tilting levers in a downwardly tilted position and clamps 85 them upon their respective supports 1 by the loose engagement of holes or inclosures 8 with said supports. This downwardly tilted or clamping position prevents any downward movement of the base plate A by 90 means of the initial clamping effect of spring 10 and the increased clamping effect of any downward stress placed upon base plate A and transmitted to said levers 6 through pivot pins 5. 95

It will be noted that while spring 10 holds levers 6 in an initial clamping position respecting downward movement the position of levers 6 allows the device to be moved upward respecting supports 1 without interference. To move the device downwardly upon supports 1, levers 6 are manually tilted against spring 10 to a position at which there is no clamping action of holes or inclosures 8 upon supports 1. 100

It will be noted that though the inclosures 8 are shown as holes in the drawings it is not necessary that supports 1 be completely

encircled by said inclosures. It is sufficient if there be a substantial bearing of said inclosures upon supports 1 at the far and near side of the support respecting pivot pins 5, 5 so that the clamping action may be effected.

In the operation of the device the base plate A and appended parts are moved along supports 1 in the manner hereinbefore described until the device is in proper relation 10 with the load. The jack screw 14 is then manipulated to lift the load through threaded plate 17 and beam 18.

Having thus fully described my invention, I claim:

- 15 1. In a support, a base plate comprising two abutting members secured together, a downwardly extending ear on each member, horizontally disposed pivot pins mounted on said ears, a lever pivoted at a point intermediate the ends thereof to respective pivot pins and having vertically disposed inclosures formed at the outer ends thereof, the inner ends thereof extending toward each other, and a single spring means engaging 20 the inner ends of said levers and adapted to normally retain said levers in a tilted position relative to said base.
- 20 2. In a support, a base plate comprising two abutting members secured together, a downwardly extending ear on each member, horizontally disposed pivot pins mounted in 30 said ears, a lever pivoted at a point intermediate the ends thereof to respective pivot pins and having vertically disposed inclosures formed at the outer ends thereof, the inner ends thereof extending toward each other and having upwardly extending lugs formed thereon, a downwardly extending lug formed on said base, and a coiled compression spring disposed 35 between said inner 40

ends and said base and engaging said lugs with its respective ends.

3. In a support, a base plate comprising two abutting members having coincident hemispherical depressions on the abutting 45 surfaces thereof and secured together, a jack screw having its lower end journaled therein, a downwardly extending ear on each member, horizontally disposed pivot pins mounted in said ears, a lever pivoted at a 50 point intermediate the ends thereof to respective pivot pins and disposed between said ears and having vertically disposed inclosures formed at the outer ends thereof, the inner ends thereof extending toward each 55 other, and a single spring means engaging the inner ends of said levers and adapted to normally retain said levers in a tilted position relative to said base.

4. In a support, a base plate comprising 60 two abutting members having coincident hemispherical depressions on the abutting surfaces thereof and secured together, a jack screw having its lower end journaled therein, a downwardly extending ear on each member, horizontally disposed pivot pins mounted on said ears, a lever pivoted at a 65 point intermediate the ends thereof to respective pivot pins and having vertically disposed inclosures formed at the outer ends 70 thereof, the inner ends thereof extending toward each other and having upwardly extending lugs formed on said inner ends, a downwardly extending lug formed on said base and disposed above said first mentioned 75 lugs, and a coiled compression spring disposed between the base and the inner ends of said levers and engaging said lugs.

In testimony whereof I affix my signature.

JEFFERSON R. LOWRY.
